UNITED STATES PATENT OFFICE.

JAMES A. CAMERON AND GUSTAF BIRGER BIRCH, OF BROOKLYN, NEW YORK, AS-SIGNOR TO CAMERON MACHINE COMPANY, OF BROOKLYN, NEW YORK, A CORPORATION OF NEW YORK.

SLITTING MEANS.

Application filed June 9, 1920, Serial No. 387,620. Renewed December 9, 1922. Serial No. 490,727.

To all whom it may concern:

Be it known that we, JAMES A. CAMERON and GUSTAF B. BIRCH, citizens of the United States, and residents of the borough of Brooklyn, in the city of New York and State of New York, have invented certain new and useful Improvements in Slitting Means, of which the following is a specification.

This invention relates generally to slitting means and more especially to the type in which overlapping and laterally engaging shearing members are employed, this application being a division of that filed October 1st, 1918, Ser. No. 256,447.

15 The main object and feature of the invention is the provision of suitable means for rendering the parts accessible in a construction in which both shearing members are positively driven.

20 In the accompanying drawings, a concrete form of a preferred embodiment of the invention is shown, but it is to be understood that changes and modifications may be made without departing from the spirit and scope 25 of the invention:

Fig. 1 is an end elevation of slitting means embodying the invention:

Fig. 2 is a view, looking in the direction of the arrow 2 of Fig. 1, showing one of the 30 cutters in section:

Fig. 3 is a detail view of a modified form of slitters partly in section:

The specific machine shown includes two main end frames 5 mounted on a suitable 35 base and rigidly held in respect to each other. The web of paper 6 to be slit is shown as passing over guiding rollers 7 and 8 mounted in the end frames, roller 8 being a rewinding drum which with rewinding 40 drum 4, acts as a surface rewinding device for the coils 60 and also acts to draw the web through the shears at a constant speed.

The means for slitting the paper comprises 45 slitting members 19 and 20 in the form of overlapping rotating shear-cutters arranged in sets, one member of each set being carried by a rotating shaft so that both slitting members are positively driven. Cutters 19 are mounted on rotatable shaft 46 carried by 50 arms 47 on a rocking support 3 while cutters 20 are carried by a rotatable shaft 48 mounted in the end frames. In effect, therefore, said cutter members are arranged in two groups, one member of each set being in one

group on shaft 48 and the other member of 55 each set being in the other group on shaft 46 carried by arms 47 on rocking support 3.

Rocking support 3 is suitably mounted at one end to move with a slide 22, the movement being in a direction parallel to the axis 60 of the rocking support to move the group composed of members 19 laterally in unison. This slide moves in guides 23 and is actuated by means of threaded stem 24 rotating idly in the slide being prevented from lengthwise 65 displacement therein by means of collar 25 and shoulder 26, the stem being in threaded engagement with a bushing 27 carried by guides 23. Check nuts 28 limit the movement in one direction so that slide 22 can 70 always be returned to the same position. The other end of rocking support 3 slides in bearing 23a.

Means are provided for rocking the support to move member 19 edgewise in unison. 75 A crank arm 13, carried by rocking support 3, is, at its outer end, internally threaded at right-angles to the axis of the rocking support. Extending through the internally threaded portion of the crank arm is an externally threaded member 14 rotatable by means of a handle 15. The unthreaded end 30 of member 14 is tiltably supported in bearing 31, which has a shank 32 freely rotatable in an extension 29 carried by slide 80 22. In this manner, when stem 14 is rotated, bearing 31 will prevent lengthwise displacement of the stem while allowing idle rotation and tilting and, therefore, crank arm 13 will be moved, carrying with it rocking support 3. 85

Cutters 19 and 20 are driven by the following means: Shaft 48 of cutters 20 is driven by pulley 45 and carries a sprocket 49 from which a chain 50 extends to sprocket 95 51 on rocking support 3 on which is a spur gear 52 meshing with a spur gear 53 on shaft 46 that carries cutters 19. Thus, both shafts 46 and 48 are driven positively and in opposite directions. 100

Cutter 19 has a sleeve 54 sliding in groove 55 and interposed between this sleeve and a collar 56 is a spring 57 that normally tends to urge 19 against 20. A stop 58 limits the movement of cutter 19 to the right in Fig. 2 105 when rocking support 3 is moved lengthwise of its axis. By adjusting collars 56 and stops 58, the tension with which each set of

overlapping shears engage can be varied independently of that of any other set, and after members 19 are moved sidewise in unison to separate 19 and 20, they may be 5 restored to their original position and tensional relation, as will be understood. In Fig. 3, cutter 19 is devoid of springs and is merely secured by a bolt 59 to shaft 46.

We claim:

- 10 1. Slitting means comprising a plurality of sets of rotatable overlapping shearing members arranged in two opposed groups, the members of each set engaging laterally with each other, means for positively driving both members of each set, means for moving the members of one group laterally and in unison with respect to the other group, and means for moving the members of the same group edgewise and in unison 15 to separate the members of opposed groups.
- 15 2. Slitting means comprising a plurality of sets of rotatable overlapping shearing members arranged in two opposed groups, the members of each set engaging laterally 20 with each other, means for positively driving both members of each set, means for varying, regardless of the members of any other set, the lateral relation between the members of each set, means for moving the members of one group laterally and in unison with regard to the other group, and means for moving the members of the same group edgewise and in unison to separate the members of opposed groups.
- 25 3. Slitting means comprising a plurality of sets of rotatable overlapping shearing members arranged in two opposed groups, the members of each set engaging laterally 30 with each other under tension, means for positively driving both members of each set, means for varying regardless of the members of any other set, the amount of tension with which the members of each set shall engage laterally, means for moving the members of one group laterally and in unison 35 with regard to the other group, and means for moving the members of the same group edgewise and in unison to separate the members of opposed groups.
- 40 4. Slitting means comprising opposed slitting members, rotatable shafts carrying said slitting members, a rocking support carrying one of said shafts, means for rocking said support, a driven member on said rocking support, means for driving the shaft carried by the rocking support from the driven member on the latter, and means for driving the other shaft.
- 45 5. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmis-
- 50 6. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmis-
- 55 7. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmis-
- 60 8. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmis-
- 65 9. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmis-

driven member on the latter, means for driving the other shaft, and means for adjusting the rocking support lengthwise of its axis.

6. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, and flexible transmission means between said other shaft and said rocking support.

7. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, and flexible transmission means between said other shaft and said rocking support, and means for adjusting the rocking support lengthwise of its axis.

8. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmission means between said other shaft and said rocking support, slitting means consisting of two opposed groups of slitting members arranged on said shafts in complementary overlapping sets.

9. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmission means between said other shaft and said rocking support, slitting means consisting of two opposed groups of slitting members arranged on said shafts in complementary overlapping sets, and means for moving the rocking support lengthwise of its axis.

10. Slitting means comprising: opposed slitting members, rotatable shafts carrying said slitting members, a rocking support carrying one of said shafts, means for rocking said support, a driven member on said rocking support, means for driving the shaft carried by the rocking support from the driven member on the latter, means for driving the other shaft, flexible transmis-

- sion means between said other shaft and said rocking support, slitting means consisting of two opposed groups of slitting members arranged on said shafts in complementary overlapping sets, a crank arm carried by the rocking support internally threaded at right-angles to the axis of the latter, a threaded member in engagement with the threaded portion of the crank arm, and a bearing tiltably supporting the threaded member and with which the latter has idle rotatable engagement to thereby admit of rocking the crank arm and threaded member when the latter is rotated.
- 15 11. Slitting means comprising: opposed slitting members, rotatable shafts carrying said slitting members, a rocking support carrying one of said shafts, means for rocking said support, a driven member on said 20 rocking support with its axis in alinement with the axis of said rocking support, means

for driving the shaft carried by the rocking support from the driven member on the latter and means for driving the other shaft.

12. Slitting means comprising: opposed slitting members, rotatable shafts carrying said slitting members, a rocking member mounted for axial adjustment carrying one of said shafts, means for rocking said rocking member, a driven member on said rocking member, means for driving the shaft carried by the rocking member from the driven member on the latter, means for driving the other shaft, and means for adjusting the rocking member lengthwise of its axis. 25 30 35

Signed at the borough of Brooklyn, in the county of Kings, city and State of New York, this 5th day of June, 1920.

JAMES A. CAMERON.
GUSTAF BIRGER BIRCH.
